UNITED STATES PATENT OFFICE.

WYMAN N. HILL, OF EAST HAMPTON, CONNECTICUT, ASSIGNOR TO THE N. N. HILL
BRASS CO., OF EAST HAMPTON, CONNECTICUT.

TOY TELEPHONE.

Application filed April 15, 1924. Serial No. 706,624.

To all whom it may concern:

Be it known that I, WYMAN N. HILL, a citizen of the United States, residing at East Hampton, in the county of Middlesex and State of Connecticut, have invented a new and useful Improvement in Toy Telephones; and I do hereby declare the following, when taken in connection with the accompanying drawings, and the characters of reference 5 marked thereon, to be a full, clear, and exact description of the same, and which said drawings constitute part of this application, and represent, in—

Fig. 1 a front view of a toy telephone constructed in accordance with my invention.

Fig. 2 a plan view of the same.

Fig. 3 a sectional view on the line 3—3 of Fig. 2.

Fig. 4 a perspective view of the bell-plate 20 detached.

Fig. 5 a perspective view of a modified form of bell-plate.

This invention relates to an improvement in toy telephones and particularly to toy 25 telephones of the desk type. In the usual construction of toys of this character, a bell is mounted on the instrument and provided with a lever by which the bell is sounded, but this necessitates the operation of a lever. 30 The object of this invention is to provide a toy telephone with a bell which will be sounded by merely shaking the instrument, and the invention consists in the construction as hereinafter described and particularly recited in the claims.

In carrying out my invention, I employ a standard 10, preferably of wood, mounted upon a base 11 and having affixed to its upper end the simulation of a transmitter 12. 40 Mounted at one side of the standard is a receiver-hook 13 to support the simulation of a receiver 14, which is connected by a cord 15 with the base 11. The receiver-hook is mounted in place by driving its shank 16 into a hole formed for it in one side of the standard 10. At the back of the standard 45 there is a hole to receive the shank 17 of a flat plate 18, the shank being provided with a boss 19 to assist in holding the plate in a horizontal position. Mounted on the plate 50

are two posts 20 supporting gongs 21 and 22, the lower ends of the posts being upset in the plate and the upper ends in the gongs, and within the gongs are loose strikers 23 and 24, which are metal balls, so that, when the instrument is shaken, the balls will strike the gongs and produce a ringing sound.

While I prefer to employ two gongs, it is obvious, as indicated in Fig. 5 of the drawings, that the plate may correspond to the size of a single gong.

With this construction, the toy is provided with a sounding device, simple in construction, cheap to form and assemble, and which does not require the operation of a lever to 65 ring the bells.

I claim:

1. A toy telephone, comprising a standard and a plate mounted on one side thereof at a right angle thereto, a post vertically mounted on said plate, a gong mounted on the upper end of said post, with its edge close to the surface of the plate, and a loose striker enclosed between the gong and plate.

2. A toy telephone, comprising a standard, a plate formed on one side with a stem inserted into the said standard in a plane at right angles thereto, a post vertically mounted on said plate in a plane parallel with said standard, a gong secured to the upper end 80 of said post, with its edge close to the surface of the plate, and a loose striker enclosed between said gong and plate.

3. A toy telephone, comprising a standard, a plate formed with a shank on one side, provided with a boss and entered into the said standard in a plane at right angles thereto, two posts mounted on said plate in planes parallel with the plane of the said support, a gong mounted on each of said 90 posts, with their edges close to the surface of the plate, and a striker enclosed between each of said gongs and the plate.

In testimony whereof, I have signed this specification in the presence of two sub- 95 scribing witnesses.

WYMAN N. HILL.

Witnesses:

NORMAN N. HILL,
NORMAN W. HILL.
